UNITED STATES PATENT OFFICE.

JAMES LAKE, SR., OF BROOKLYN, NEW YORK.

HAT-PRESSING MACHINE.

Application filed June 21, 1922. Serial No. 569,899.

To all whom it may concern:

Be it known that I, JAMES LAKE, Sr., a citizen of the United States, residing at Brooklyn, in the county of Kings and State 5 of New York, have invented certain new and useful Improvements in Hat-Pressing Machines, of which the following is a specification.

This invention relates to hat shaping means of the class in which the coacting means for exerting the required pressure on a hat crown or hat brim comprise on the one hand a heated metallic matrix or mold and on the other an inflatable member to 10 oppose a yielding pressure on the matrix for compressing the interposed brim or crown. The machine herein shown and described is intended for operating on hats already 15 either but crudely formed, as in the case of straw hats, or almost perfectly shaped, as in the case of felt and the like so-called "body" hats, and it is designed especially 20 for treating the better grade of hats.

The principal objects are to provide pressure means having these advantageous characteristics, to wit: that the product thereof will represent uniformly the highest grade of workmanship; and that for adapting said means for operating on brims or crowns of 25 different sizes or shapes by substituting one matrix or mold for another changes only will have to be made in the means complementary to such matrix or mold which affect parts that are of relatively little bulk 30 and weight and which do not require disestablishing the connections by which the fluid for inflating such complementary means is introduced, so that time is saved, less attention and skill to operate the 35 machine and keep it in order are required, and little space is needed for storage of exchange parts.

The invention is not concerned with any particular instrumentalities for causing one 40 of the said coacting pressure means to move toward and from the other; therefore only the simplest form of press herein is illustrated in which said means are arranged. The one of the coacting means which constitutes the matrix or mold is herein also 45 shown as of the simple one-piece type, with the crown and brim forming portions in rigid relation to each other, but that is also immaterial to the present invention.

50 In the drawing,

Fig. 1 is a side elevation of a press con-

taining the improved coacting pressure means;

Fig. 2 shows said means mainly in vertical section, this view being at right angles 60 to Fig. 1;

Fig. 3 shows in section the inflatable die;

Fig. 4 shows in plan one of the platens;

Fig. 5 shows in section fragments of two 65 of the platens; and

Fig. 6 shows in section two of the collets *r*.

Let *a* be the fixed structure of a suitable press and *b* the movable structure thereof 70 movable toward and from the structure *a* and operated by the treadle *c* connected in any suitable way with the depending portion (as a pair of rods) *b'* of said structure *b*.

The metallic matrix or mold *d* is here 75 shown carried by the structure *a*, its flange *d'* being removably secured by nuts *a''* on pillars *a'* forming upstanding parts of the structure *a*. Said matrix or mold has a working face facing the movable structure *b*, the same comprising a concave crown-shaping portion or cavity *d²* and an annular brim-shaping portion or surface *d³*. It is not indispensable that the matrix or mold be the upper one of the two coacting pressure means, but it is better so since by that arrangement the hat appears right side up to the attendant and it is the top surface of the hat which requires the more particular attention. The matrix or mold is here 90 shown as hollow so as to contain steam as a heating medium, the steam connections not being shown; it may be adapted to be heated in any other way.

Means coacts with the cavity *d²* of the 95 matrix to shape the crown which is of well known form in so far as it includes an inflatable die having an inflatable bulbous die proper *e* to be received by said cavity and having means for supporting and inflating it, as the fluid-conducting pipe or tubular standard *f* to the upper end of which it is suitably connected; according to a known construction this die may be vertically adjustable relatively to the remaining or brim forming part of the lower of the two coacting pressure means in order to be adapted for cavities *d²* of varying depth (that is, in order to coact with matrices designed for 100 the shaping of hat crowns of different heights), as by having the standard *f* threaded into a nut *g* which is revolvable in a part 105 110

of the movable structure b , as the cross-head b'' connecting the rods b' , the structure $e-f$ being splined with b at h and so kept from turning. As usual in these machines the structure $e-f$ will have valves (not shown) for controlling the admission to and release therefrom of the inflating fluid, it being understood that usually the inflating is made to take place after the die 10 is fully contained within the cavity d^2 so that such inflating is the factor causing the pressing and consequent shaping of the hat crown. Where cavities d^2 of different depths are presented the die is adapted 15 thereto by simply adjusting it up or down as aforesaid. But where cavities of different head-sizes, i. e., diameters, are presented the die is adapted thereto as follows: The element e or inflatable die proper is 20 adapted to coact directly with the cavity of smallest head-size; for the cavities of the larger head-sizes there are intermediaries i , each in the form of a rubber cap and all having inside the same size as the exterior of the 25 die proper e but so graded in thickness that exteriorly they respectively have sizes to suit such cavities of the larger head-sizes. It is necessary that the inflatable die (i. e., whether consisting of only the die proper or 30 such die proper with one of these caps thereon) should be elastic so as to expand when inflated and also contract when deflated for clearing the hat crown; it is also very desirable, in order to impart the proper finish 35 to the surface of the hat and prevent the material of the die proper tending to bulge locally or in spots and so produce thin places in the hat material, to form said die proper and each of the caps, which are made 40 of elastic rubber, with strata of different degrees of yieldability to pressure and with the less yieldable stratum, which is preferably fairly hard, forming the superficial portion of the member e or i , as indicated at 45 j in Fig. 3. This particular expedient is not in itself new in the art for the purpose stated, but it is when applied to a bulbous body like e or i and in particular to its upright as well as its top or arched portion, in 50 which connection it has the further advantage of desirably stiffening said upright portion so that it is better adapted to withstand the wear and tear incident to the die entering and leaving the cavity under the thrust 55 of the press and of easing the slipping-on and off (particularly the former) of the hat crown. Each cap is adapted to have a normal retaining grip on the member e , that is, a grip which will insure its descending with said member to clear the cavity on previous removal of the inflating pressure within said member; in the present example such grip is due both to friction and atmospheric pressure as an incident to the cap snugly 60 fitting member e . The caps are elastic and

each is self-contracting to a size that will enable it in its normal or contracted state to freely enter or leave the cavity with the hat crown interposed.

As for the means for shaping the brim: 70 k is a support which is here shown separate from and resting on the movable structure b of the press and may be secured thereto in any way. It has an outer upstanding continuous flange k' and also an inner upstanding flange generally designated by the character k'' , to which latter more particular reference will be hereinafter made. In the annular channel formed by this flanged support is placed what I term an annular inflatable bag means, being in the present form an elastic rubber annular tubular body l and an annular casing or envelope m therefor provided with a continuous opening or slit m' for admitting the body l . There are 75 attached to the body l tubular connections n for admitting thereto and releasing therefrom a suitable inflating fluid, and these connections may have valves (not shown) for controlling the fluid flow. The flange k' is higher than the inflatable bag means, but the heights of flange k'' and said means are about equal. In the recess formed by the bag means and flange k' is seated a flat 80 endless or continuous platen o , which has an inside perimeter substantially equal in size to and conforming in shape with the mouth of cavity d^2 and an outside perimeter of suitable shape and size to be fitted more or less loosely in said recess; the platen 85 overlies, all around, the flange k'' . Since the top of the bag means is here shown flat and horizontal the under side of the platen is shaped to correspond. Its top surface is shaped to present substantial parallelism to the surface d^3 of the matrix d . The platen is preferably made of soft rubber with its top surface hardened for a suitable depth, as at o' , in order to impart 90 a good finish to the under side of the hat brim and prevent the material of the platen tending to bulge or yield locally. The inner surface of flange k'' is substantially 95 flush, all around, with the inner edge of the platen. The flange k'' is beveled (preferably with a rounded bevel) at the top thereof, exteriorly, as at p and the shape of the bag means is preferably such that at m'' it reaches into the crevice produced by this 100 bevel, so that on inflation the bag means 105 will exert pressure against the surface d^3 clear to the margin of the cavity d^2 . It is very important that the thickness of flange k'' should not be a factor in preventing the 110 pressure exerted by the bag means from acting on the particular part of the hat where the crown and brim meet. The office 115 of the flange k'' is to limit the laterally inward bulging of the bag means when the latter is inflated so that, since it is also 120

- limited against bulging downwardly and laterally outward by k and k' , the pressure it exerts will be concentrated upwardly and can have no undue influence on the die e .
- 5 Its office is also to protect the inner edge of the more or less limber platen from disturbance due to the laterally expanding action of said die e which, without interposition of the flange, circumferentially
- 10 meets the inner perimeter of the platen so that the two coact to impart a nice finish to the said part of the hat where the crown and brim meet. When the matrix is changed for another a corresponding change
- 15 must be made as to the platen; wherefore the necessary equipment will include at least as many platens as there are matrices, such platens (with respect to changes in head-sizes) all having the same outside
- 20 diameters but varying inside diameters (Fig. 5). Likewise a corresponding change must be made with respect to the flange k'' . The preferred construction for this purpose is one wherein there is a fixed basal
- 25 portion g upstanding from support k and a collet r which has at the top the mentioned exterior bevel p and fits within the portion g and has an exterior undercut shoulder s to rest on the top of said portion, the collet
- 30 being held against rising by a pin t removably arranged in alined holes in the support k and the collet. There will of course be as many collets as there are matrices for different head-sizes, they all having the same
- 35 outside diameters but varying inside diameters and also varying angles of bevel p (Fig. 6).
- In the operation of the press, a hat will usually have both its crown and brim acted
- 40 upon or shaped upon a single closing of the press. The press being closed with the hat A in position on the lower one of its two coacting means and $e-f$ adjusted vertically to suit the particular depth of the cavity d^2 the
- 45 fluid is admitted for inflating the inflatable die and the bag means; the press is not closed to such an extent that the beveled edge of the collet impinges with any appreciable pressure against the inner margin of
- 50 the platen, as that would either disturb such margin undesirably, by wedging it outward, or pinch it, and would in addition involve mechanical pressure on the hat when fluid pressure everywhere is preferable. (So far
- 55 as my invention is concerned, it is not material if the inflating of the means $e-f$ occurs simultaneously or first one and then the other.) The inflatable die coacts with the matrix cavity d^2 to press and shape the
- 60 crown. The bag means, through the medium of the platen, coacts with said matrix surface d^3 to press and shape the brim. No leakage can occur because the element l is a one-piece jointless expandible structure, the
- 65 term "bag means" being intended to define an inflatable member all of whose wall structure is more or less flexible and integral. The inflatable die and bag means are always independent of each other on account of the intervening flange k'' , which like the support k and its flange k' is rigid, and said flange also protects the platen from the bulging action of the inflatable die. Finally, whenever the matrix is changed for another
- 70 changes otherwise required are very readily effected. Thus, when but the crown height is changed structure $e-f$ only requires vertical adjustment. When the head-size is changed, it is only necessary to change the small, light and easily and quickly removable parts i , r and o . When the brim-shape is changed only the part o needs to be changed. The bag means and its support remain permanently in the machine for all shapes and sizes. Changes affecting head-sizes or brim-
- 75 shapes in previous machines required removing not only the inflatable crown die but, as an entirety, the inflatable brim pressure means, with incidental disconnection of the fluid conducting means for both said die and pressure means; it further required extensive storage facilities for these larger structures in the multitude of sizes and shapes that they were adapted to produce,
- 80 since the work- or hat-contacting surfaces were integral parts of them.
- In the present instance the wall-like portions formed by the platen and flange k'' are shown separable, the platen being of rubber and the flange of metal, and the latter at least at its basal part being rigid with respect to support k . But these details are not indispensable, it being a part of my invention to arrange such portions in angular relation to each other for controlling the expansion radially inward and upward of the bag means.
- Having thus fully described my invention, what I claim as new and desire to secure by Letters Patent is:—
1. In a hat pressing apparatus, an inflatable expandible bulbous rubber member forming a crown-shaping die coactive with a crown-shaping matrix cavity, the same having throughout strata of different degrees of yieldability to pressure and having the less yieldable stratum the superficial exterior portion of the member.
- 110
2. In a hat pressing apparatus, a bulbous crown-shaping die coactive with a crown-shaping matrix cavity and including an inflatable inner bulbous expandible member and an expandible rubber cap fitted over said member.
- 120
3. In a hat pressing apparatus, a bulbous crown-shaping die coactive with a crown-shaping matrix cavity and including an inflatable inner bulbous expandible member and a self-contracting but expandible cap fitted over said member.
- 125
- 130

4. In a hat pressing apparatus, a bulbous crown-shaping die coactive with a crown-shaping matrix cavity and including an inflatable inner bulbous expandible member and a self-contracting but expensible cap applied over and having a normal retaining grip on said member.
5. The combination of coacting hat pressing means, one having a crown pressing cavity and around the cavity a brim-pressing surface and the other including a die to enter the cavity and coact with the surface thereof to form the hat crown and around the die a platen to coact with the brim-pressing surface to press the hat brim and bag means backing said platen, with mechanism to move one of said first-named means toward and from the other.
6. The combination of coacting hat pressing means, one having a crown cavity and around the cavity a brim-pressing surface and the other including a flexible concavo-convex die to enter the cavity and adapted to receive pressure internally thereof and thereby to coact with the surface of said cavity to form the hat crown and said other one of said means also having around the die a relatively thin pressure-transmitting medium to coact with the brim-pressing surface to press the brim and having an edge thereof presented to the die, with mechanism to move one of said means toward and from the other including a rigid flange surrounding the die and between which and the brim-pressing surface said edge of said medium is interposed.
7. The combination of coacting hat pressing means, one having a crown cavity and around the cavity a brim-pressing surface and the other including a flexible concavo-convex die to enter the cavity and adapted to receive pressure internally thereof and thereby to coact with the surface of said cavity to form the hat crown and said other one of said means also having around the die a relatively thin pressure-transmitting
- medium to coact with the brim-pressing surface to press the brim and having an edge thereof presented to the die, with mechanism to move one of said means toward and from the other including a rigid flange surrounding the die and between which and the brim-pressing surface said edge of said medium is interposed, and bag means around the flange to apply pressure against said medium.
8. The combination of coacting hat pressing means, one having a crown cavity and around the cavity a brim-pressing surface and the other including a flexible concavo-convex die to enter the cavity and adapted to receive pressure internally thereof and thereby to coact with the surface of said cavity to form the hat crown and said other one of said means also having around the die a relatively thin pressure-transmitting medium to coact with the brim-pressing surface to press the brim and having an edge thereof presented to the die, with mechanism to move one of said means toward and from the other including a rigid flange surrounding the die and between which and the brim-pressing surface said edge of said medium is interposed, and bag means around the flange to apply pressure against said medium.
9. The combination of coacting hat pressing means, one having a crown cavity and around the cavity a brim-pressing surface and the other including a die to enter the cavity and coact with the surface thereof to form the hat crown and around the die inflatable bag means to coact with said brim-pressing surface to press the hat brim, with walls arranged in angular relation to each other and one interposed between the bag means and die and the other between said bag means and brim-pressing surface.

In testimony whereof I affix my signature.
JAMES LAKE, SR.
